BOBBIN CLEANING MACHINE

Albert J. Owler, Northbridge, Mass., assignor to
 Paul Whitin Manufacturing Company, Northbridge, Mass., a corporation of Massachusetts

Application April 1, 1936, Serial No. 72,084

5 Claims. (Cl. 28—19)

This invention relates to a machine for removing weft ends from bobbins which have been ejected from automatic looms before complete exhaustion of the weft thereon. These ejected bobbins commonly have from one to three or four yards of weft remaining on the barrel of each bobbin, and the removal of these weft ends constitute a somewhat troublesome mill problem.

It is the general object of my invention to provide an improved machine for removing the weft ends from the bobbins without injury to the bobbins or scratching of the weft-engaging surface thereof.

To the attainment of this object I provide a rotated container, by the operation of which the bobbins are caused to coat on each other in such manner as to entangle and unwind the weft ends therefrom without engagement of the bobbins by clamping jaws or other mechanical devices.

20 My invention further relates to arrangements and combinations of parts which will be herein-after described and more particularly pointed out in the appended claims.

25 A preferred form of the invention is shown in the drawing, in which

Fig. 1 is an end elevation of my improved bobbin cleaning machine;

Fig. 2 is a sectional plan view, taken along the line 2—2 in Fig. 1;

30 Fig. 3 is a sectional end elevation of the rotated container;

Fig. 4 is an enlarged detail sectional view of certain parts to be described;

35 Fig. 5 is a partial view of a bobbin having a weft end thereon, and

Fig. 6 shows a mass of weft ends as produced by the operation of the machine.

Referring to the drawing, I have shown a supporting frame 10 having cross bars 11 on which bearings 12 are mounted. A revolvable container C is provided with end gudgeons 13 and 14 rotatably supported in the bearings 12. A gear 15 is fixed to the gudgeon 14 and is engaged by a pinion 16 on a countershaft 17 rotatable in fixed bearings 18 and provided with tight and loose pulleys 19 and 20, with which pulleys a driving belt 21 is associated. By shifting the belt 21 from the loose to the tight pulley, the container C may be rotated for any desired period.

50 The container C preferably comprises octagonal wooden heads 24 to which wooden side plates 25 are firmly secured in any convenient manner, as by brackets 26 and bolts 27 (Fig. 4).

55 Before the side plates 25 are secured to the

heads or ends 24, each side plate is preferably lined with a cushioning frictional material. As indicated in Fig. 4, the lining may comprise two layers of sheet rubber 28 between which are interposed two layers of canvas 29. Preferably the ends of these layers are clamped between the heads 24 and side plates 25, as also indicated in Fig. 4.

Certain of the side plates are mounted for convenient removal to afford access to the interior of the container C. In Figs. 1 and 3, I have indicated a cover section 30 comprising two adjacent side plates secured together, said section 30 being hinged at 31 to an adjacent side plate 25 and being provided with a latch 32 by which it may be retained in closed position.

Blocks 40 are secured to the inner faces of the side plates 25 and of the cover structure 30 as indicated in Figs. 2 and 3, these blocks being preferably formed of wood and being covered with rubber and canvas as previously described. Additional blocks 41 may also be provided, preferably having curved outer surfaces and being also covered with rubber and canvas.

The frame 10 may support a bracket 45 having a slide or track for a bobbin tray 46 adapted to receive a load of bobbins transferred to it from a mill truck 47. The frame 10 may also support a slide or track 50 for a second or receiving tray 51 in which the load of bobbins from the rotatable container C may be dumped after being cleaned. I have also indicated a second truck 52 to which the cleaned bobbins may then be transferred.

Having described my improved bobbin cleaning machine, I will now describe the operation and advantages thereof.

A load of 500 to 600 bobbins is placed in the tray 46, the cover section 30 is opened and the tray is pushed forward so that the bobbins to be cleaned may be dumped into the container. The container is then closed and is rotated for a desired period, commonly about five or six minutes.

The bobbins B when placed in the container each have a bunch of weft W (Fig. 5) near the butt of each bobbin. As the bobbins are tumbled about within the rotating container, they coat on each other and the weft ends of the different bobbins quickly become entangled and are unwound from the bobbins. The operation is much facilitated by the action of the blocks 40 and 41 which agitate the bobbins and cause them to more effectively coat on each other.

After the machine has been operated for a few minutes, the cover section is unfastened and the

5 container is rotated to bring the opening at the bottom, whereupon the load of cleaned bobbins will be deposited in the receiving tray 51, in which they may be pulled forward for inspection and for removal of the waste yarn masses.

10 It is found in actual operation that the weft ends collect in large masses M of tangled yarn, such as is indicated in Fig. 6, which masses may be readily picked out from the tray 51 before the cleaned bobbins are dumped into the truck 52.

15 It is also found by experience in actual use that 98 to 99% of the bobbins will be completely cleaned when removed from the container after five or six minutes operation of the machine. The few bobbins not completely cleaned are returned to the container with the next load of bobbins to be cleaned.

20 My improved bobbin-cleaning machine has two very important advantages. In the first place it handles bobbins with great rapidity, one machine easily cleaning upwards of five thousand bobbins per hour.

25 A further and even more important advantage lies in the fact that the bobbins are cleaned without engagement by any mechanical device. Consequently the bobbins are not injured and the yarn-engaging surfaces of the bobbins are not scratched or abraded. This is a particularly valuable feature when using silk or rayon or any 30 other fine or delicate weft.

Having thus described my invention and the advantages thereof, I do not wish to be limited to the details herein disclosed, otherwise than as set forth in the claims, but what I claim is:—

35 1. A machine for unwinding and removing waste yarn from loom bobbins comprising a re-

5 volvable container having a cushioned frictional inner surface and a plurality of inwardly projecting obstructions on the inner face of said container, a closure for said container, and means to rotate said container.

2. A machine for unwinding and removing waste yarn from loom bobbins comprising a re- 10 volvable container having a cushioned frictional inner surface and a plurality of rubber-covered blocks secured to said inner surface, a closure for said container, and means to rotate said container.

3. A machine for unwinding and removing waste yarn from loom bobbins comprising a re- 15 volvable container having a plurality of flat sides each provided with a sheet rubber and canvas lining, a plurality of cushioned blocks secured to the inner faces of said flat sides, a closure for said container, and means to rotate said container.

4. A machine for unwinding and removing waste yarn from loom bobbins comprising a re- 20 volvable container having a plurality of flat sides and a plurality of cushioned blocks secured to the inner faces of said flat sides, a closure for 25 said container, and means to rotate said container.

5. A machine for unwinding and removing waste yarn from loom bobbins comprising a re- 30 volvable container having a plurality of inwardly projecting obstructions on the inner face of said container, a closure for said container, means to rotate said container, means to feed bobbins to said container, and means to receive bobbins ejected from said container.

35 ALBERT J. OWLER.
